UNITED STATES PATENT OFFICE

2,354,080

AUTOMATIC FIREARM BREECHBLOCK STOP

George Webb, Hartford, Conn., assignor to Colt's Patent Fire Arms Manufacturing Company, Hartford, Conn., a corporation of Connecticut

Application April 6, 1942, Serial No. 437,852

6 Claims. (Cl. 89—3)

This invention relates to a breech block stop for an automatic firearm. The invention is particularly applicable to automatic firearms of the caliber 37 mm. automatic cannon type, but its application is not restricted to guns of this type since the principles of the invention may be applied to guns having different calibers and of different constructions wherein breech block stops of the type disclosed herein may be utilized.

The breech block stop disclosed in this application comprises improvements over those disclosed in U. S. Patent 1,525,065 to Browning, U. S. Patent 2,297,640 to Webb, and co-pending application, Serial No. 325,405, filed March 22, 1940.

It is an object of the present invention to provide a breech block stop which is horizontally movable forward to remove the stop from its normal position for stopping or arresting the downward movement of the breech block when it is desired to completely remove the breech block from the firearm.

It is another object of the invention to provide a spring for biasing the breech block stop to its normal position in which it is adapted to stop the downward movement of the breech block and hold the breech block in its normally lowermost position.

A further object of the invention is to provide positioning means on the breech block stop adapted to cooperate with a slot or recess in the bottom of the breech block to prevent horizontal movement of the lower end of the breech block in a direction transverse to the axis of the firearm.

Other details and objects of the invention will become apparent from considering the following specification.

The accompanying drawing shows the embodiment of the invention which is deemed preferable, but it will be understood that the drawing is intended for illustrative purposes only and is not to be construed as defining or limiting the scope of the invention, the claims forming a part of this specification being relied upon for that purpose.

In the drawing,

Fig. 1 is a fragmentary side elevation of an automatic firearm in which a breech block stop comprising the present invention is shown in its normal position and the breech block is in its breeched position.

Fig. 2 is a fragmentary vertical sectional view taken along the line 2—2 of Fig. 1 but showing the breech block in its normally lowermost position and omitting certain parts of the firearm.

Fig. 3 is a fragmentary vertical sectional view taken along the line 3—3 of Fig. 1.

Fig. 4 is a fragmentary side elevation of the breech block stop shown in Fig. 1, this elevation being partly in section along the line 4—4 of Fig. 3, the breech block being in its normally lowermost position.

Fig. 5 is a fragmentary side elevation similar to Fig. 4 but showing the breech block stop retracted and the breech block partially removed from the firearm.

The automatic firearm, hereinafter referred to as a gun, to which the present invention is applicable is of the type illustrated in complete detail in said co-pending application, Serial No. 325,405, and said gun is also similar to the type illustrated in said Browning Patent 1,525,065. Inasmuch as the present invention deals with the construction of the breech block stop, only sufficient details of the entire gun are herein described and illustrated to form a basis for understanding the characteristics of the details and functions of the breech block stop. For an illustration and description of the entire gun, attention is invited to said above-mentioned patent and application.

Guns of the type to which the present invention is applicable are well adapted for use in airplanes, although their use is not so limited. Such guns are normally mounted in various predetermined positions in airplanes and, especially during combat, the airplane and gun will assume a great many different positions while the airplane is being maneuvered. It is essential that the gun be able to fire while in any of these positions. However, the mounting means for the breech block of guns of this type is such that after the operating lever has moved the breech block to open position away from the breech of the barrel, the operating lever disengages from the breech block, whereby the breech block is free to move in its guideways under the force of gravity.

To control the movement of the breech block after such release, stop means have been provided to limit the movement of the breech block away from the breech end of the barrel. Said stop means are attached to the gun by suitable mounting structure whereby the stop may be readily retracted from the path of movement of the breech block to permit the breech block to move past the stop and thus be entirely removed from the gun. Furthermore, it has been found that under certain situations occurring during maneuvering of an airplane, such as when "bank-

ing," if the breech block is in its lowermost position and resting on the stop, centrifugal force will tend to throw the lower end of the breech block to one side of its normal position in which it is normally engaged by the operating lever whereby, when the operating lever is moved forward to engage in the slot in the lower end of the breech block, the slot will not be in proper alignment to receive the operating lever and a malfunction of the gun results. To prevent the occurrence of such malfunctions due to this cause, means are provided in the present invention to maintain the lower end of the breech block against horizontal movement transversely of the gun when the breech block is in its lowermost position. Accordingly, the present invention provides suitable mechanism for controlling the movement of the breech block in all conceivable positions of operation of the gun, whereby the breech block will function properly in all such positions of the gun.

Referring to the drawing, the gun is shown disposed horizontally with its sides in upright position. With respect to Fig. 1, the forward or barrel end of the gun is toward the right while the rear end of the gun is toward the left. This position of the gun might be considered the "normal" position. All relative terms hereinafter used, such as "downward," "upward," "horizontal," "vertical," "forward," "rearward" and the like are to be considered relative to the "normal" position referred to.

The breech casing 2 houses most of the operating and movable elements of the gun. A trunnion block 3 is provided in the forward end of the breech casing. Projecting from the forward end of the breech casing and slidably disposed in the trunnion block 3 is a barrel 4 provided at its breech end with threads 4a. Also slidably disposed within the breech casing is a barrel extension 18. The forward body portion of the barrel extension is apertured and threaded to receive the threaded breech end of the barrel or tube and detachably retain the barrel in operative position with the barrel extension. The barrel extension is also provided with a pair of substantially parallel rearward extending arms 18a. The barrel extension is also provided with a depending portion or lug 18c for purposes to be described.

The barrel and barrel extension move rearward as a unit upon recoil and are returned in the forward direction by a recuperator spring 20 enclosed in a recuperator tube 21 secured to the bottom of the trunnion block 3. The spring 20 acts through a recuperator rod 22 which is connected at its rear end with the depending lug 18c on the barrel extension 18. A nut 22a threaded on the rod serves to effect connection of the recuperator rod with the lug 18c.

Carried by the barrel extension 18 is a breech block 25 which is arranged to slide substantially vertically between the parallel arms 18a of the barrel extension. The block is guided in its vertical movement by a pair of ribs 25a which are respectively disposed on opposite sides of the breech block to fit corresponding grooves formed in the arms 18a of the barrel extension. In Fig. 1, the breech block is shown in its uppermost breech-closing or breeched position. The lower portion of the breech block 25 has a rearward projection 25b and in this longitudinally widened lower portion of the breech block there is provided a T-slot or recess 25c which receives the

actuating lever for raising and lowering the breech block as will be presently explained.

Longitudinally movable within the breech casting is a lock frame 26, the upper portion of which is of such width as to permit it to move between the arms 18a of the barrel extension. Depending from the lock frame 26 is a yoke 28 to which are detachably connected two transversely spaced tension rods 29.

10 The depending lug 18c of the barrel extension supports a yoke 30 by means of a channel 30c which is formed in the lower face of the lug to provide a mounting seat for a projection 30d extending upward from the central portion of the yoke 30. The yoke and lug are suitably joined by rivets 30e, or any other suitable connecting means, whereby the yoke and lug cooperate as a substantially integral unit and for purposes of simplifying the explanation of the invention, the 15 yoke and lug may be considered a unitary member as far as the mounting of the slidable stop member, to be presently described, is concerned. The yoke is provided with projecting arms 30a, 30a as shown particularly in Fig. 3. Detachably supported in part on the arms 30a, 30a are tubes 31, 31 which receive the tension rods 29, 29 and also receive reaction or driving springs 32 surrounding the tension rods. The springs 32 abut at their rear ends against plugs 31a in the rear 20 ends of the tubes 31, and abut at their forward ends against collars (not shown) on the rods 29, 29 near the forward ends thereof.

Pivottally mounted between downward projecting lugs 26a on the lock frame, is a breech block actuating or operating lever 33. For purposes of explaining the operation of the mechanism comprising the main part of this invention, it is sufficient to briefly state that the operating lever is provided with suitable laterally projecting lugs or studs 33c, 33d and 33e. Said lugs each project from opposite sides of the operating lever and the oppositely disposed portions of the lug 33c are adapted to engage in the T-shaped slot 25c of the breech block for raising and lowering the breech block as the operating lever is moved about its pivot during the operation of the gun. Movement of the operating lever 33 is controlled and guided by the studs 33d and 33e co-acting with cam surface 35, cam groove 35a and other cams 25 and grooves (not shown) provided on the firearm. Said studs and cams are brought into engagement with each other through the movement of the lock frame 26 which carries the operating lever 33 therewith.

55 With the above-described parts of the firearm in the position shown in Fig. 1, when the firing of a cartridge or round takes place, the barrel and barrel extension move rearward against the force of recuperator spring 20. The lock frame 26, together with yoke 28 and operating lever 33, also moves rearward against the force of springs 32. In so moving, lugs 33d of operating lever 33 engage cam surfaces 35 to move the forward end of the operating lever downward and, in so moving, the lugs 33c, which are disposed in T-shaped slot 25c of the breech block, move the breech block 25 downward while the lock frame and operating lever meanwhile continue to move rearward. During the course of such rearward movement of the operating lever, the lugs 33c will be withdrawn from the rearward end of the slot 35c to thus entirely disconnect the operating lever from the breech block. The breech block, due to momentum of its initial movement, continues to move downward and, unless otherwise

opposed, would move completely from the lower end of the guideways in the barrel extension and drop from the gun.

To prevent such complete removal of the breech block during normal operation of the gun, downward movement of the breech block is normally limited or arrested by a stop which is in some respects similar to those disclosed in my previously mentioned Patent 2,297,640 and in Browning Patent 1,525,065. The construction shown herein differs, however, from the construction shown in said application and patent and has certain advantages thereover.

The yoke 30 is provided with a rearward projecting ledge or aligning means 39. Supported on the ledge and slidably thereon is a stop member 40 which is provided on its forward face with a cylindrical portion or guide member 40^a. The rearward face of the stop 40 is provided with a stop portion 40^c which is adapted to directly engage the bottom of the breech block to limit downward movement thereof. The unitary projecting lug 18^a and yoke 30 are provided with a transversely extending hole or opening which is preferably counterbored from one end to provide a cylindrical bearing 41^a which has an annular seat at its innermost end. The guide member 40^a of the stop is slidably disposed in the open end of the counterbored portion 41^a.

A guide shaft 40^a extends through the opening in the lug and yoke and is threadably connected at its rearward end to the stop 40. Said end of the shaft is also reduced in diameter and the reduced portion is formed with an annular groove 40^e. A locking pin 40^f is inserted in a suitable aperture formed in the stop in alignment with the underside of the annular groove 40^e, whereby said pin locks the shaft and stop in threaded assembly.

A helical spring 41 surrounds the shaft 40^a and the rearward end of the spring abuts against the inner end of the member 40^a and the other or forward end of the spring abuts against the annular seat on the interior of the counterbored portion 41^a. The spring 41 serves to normally bias the stop toward its rearmost position in which the stop portion 40^c is adapted to engage the bottom of the breech block to limit downward movement thereof. By this arrangement it will be seen that the spring is completely enclosed within the interior of the lug 18^a whereby the spring will be maintained relatively free from the accumulation of dirt and other extraneous material which might otherwise collect in the counterbored portion 41^a if the opening were not closed at both its ends.

To insure that the stop will not move rearward past the proper rearmost position, the outer end of the shaft 40^a is provided with an enlarged head 40^g which forms a stop means to limit or arrest the rearward movement of the stop. Preferably, the lug 18^a is provided with a suitably shaped counterbored recess 40^h to receive the head 40^g when the stop is disposed in the position shown in Fig. 4.

After the breech block has reached its normally lowermost position and is at rest on the stop 40, said stop is maintained in such position against accidental or unintentional upward movement by a spring-pressed slidably mounted detent 42 which is carried by one arm 18^a of the barrel extension, as shown in Fig. 2. The detent is located on the arm in proper position to engage the upper end of the breech block when the breech block is in said lowermost position. De-

tails of the spring-pressed detent are set forth in a co-pending application, Serial No. 314,272, filed January 17, 1940, in the name of William L. Swartz, now Patent 2,339,661 dated January

5 18, 1944. The strength of the spring normally urging the detent 42 inward is such that it will cause the detent to maintain the breech block in its lowermost position but, when the breech block is engaged by the operating lever 33 for 10 upward movement to breeched position, the spring will readily yield to permit the breech block to cam the detent to inoperative position.

When it is desired to remove the breech block 15 from the gun for inspection, cleaning, or replacement, this can be readily done by manually moving the stop member 40 forward to its inoperative position shown in Fig. 5. The breech block will then move downward by gravity, past the stop 40, as shown in said figure. When the breech block is to be replaced, it is pressed against the stop member 40 so as to force it forward and then the breech block can be pushed upward into its normally lowermost position, the stop member being pushed rearward by the 20 spring 41 to cause the stop portion 40^c to snap under the block and retain it in that position.

When the breech block is in its normally lowermost position, as shown in Fig. 2, only the upper portion of the breech block is between the guide grooves in the arms 18^a of the barrel extension. The major portion of the breech block is below the guide grooves and inasmuch as a small amount of clearance is normally allowed between the guide ribs 25^a on the breech block and the grooves in the barrel extension arms, a certain amount of horizontal movement of the lower end of the breech block may take place in both transverse and longitudinal directions with respect to the gun. Of these two movements, movement of said end of the breech block transversely of the gun is apt to cause a malfunction of the firearm if such movement is sufficient that the studs 33^a of the operating lever will not properly align with the upper horizontal portion 45 of the T-shaped slot 25^c in the lower end of the breech block. Such horizontal transverse movement of the lower end of the breech block may be produced, for example, when the gun is mounted in an airplane and the airplane is 50 "banking" in a turn. Under these conditions, the lower end of the breech block will be moved, due to centrifugal force, in a horizontal transverse direction and if such movement is appreciable, one of the lugs 33^c will abut the rear face 55 of the rearward projection 25^b rather than both of the lugs entering the slot 25^c.

To prevent the foregoing malfunction from occurring, the breech block stop is provided with a projection 40^b which, in the preferred embodiment, is formed integrally with the stop and projects upward from the stop portion 40^c a distance approximately equal to half of the length of the vertical portion of the T-slot 25^c, as clearly shown in Fig. 2. Preferably, the base of the projection 40^b is as wide as the lower portion of the T-slot and the sides of the projection respectively taper inward toward the top whereby, when the breech block is moving downward toward its lowermost position against the stop portion 40^c, if the T-slot is not exactly in its proper position to become seated on the projection, the bevelled sides thereof will cause the lower end of the breech block to be cammed into its proper transverse position on the stop.

Inasmuch as the breech block is held in said

lowermost position by the detent 42, engagement of the projection 40^b with the T-slot 25^c will be maintained and the projection will insure the proper positioning of the lower end of the breech block whereby the T-slot will receive the lug 33^c of the operating lever when the breech block is to be raised by said operating lever during the functioning of the gun. Consequently, malfunctioning of the gun due to improper positioning of the T-slot for reception of the lugs 33^c is prevented. It will be understood, of course, that the invention is not restricted to the exact size and shape of the projection shown in the preferred embodiment. Furthermore, inasmuch as the projection extends rearward no farther than the stop portion 40^c, the projection will in no way interfere with the release of the breech block when the stop is moved forward to the position shown in Fig. 5.

From Figs. 3 and 4, it will be observed that rotation of the nut 22^a on the end of the recuperator rod 22 is prevented as long as the stop 40 is in the position shown in these figures. The stop, therefore, serves a plural purpose of not only limiting the movement of the breech block, but also preventing rotation of said nut. However, when the stop is moved to the position shown in Fig. 5, the nut may be rotated if desired.

It will thus be seen that the breech block stop described above affords means for limiting the downward movement of a breech block after the operating lever has been disconnected therefrom during the normal operation of the gun. The stop is of simple and efficient construction and is adapted for expeditious manual manipulation requiring the use of no tools or mechanism of any kind. Not only does the stop provide means to arrest the downward movement of the breech block and maintain it in its lowermost position when the stop is in its normal operating position but the stop simultaneously provides means to normally prevent rotation of the nut which secures the recuperator rod to the barrel extension. Furthermore the stop includes means to prevent horizontal movement of the lower end of the breech block in a direction transverse to the axis of the gun. In addition, the stop may be manually moved forward to inoperative position against the action of its biasing spring whereby the breech block may be completely removed from the underside of the gun.

While the invention has been illustrated and described in its preferred embodiment and has included certain details, it should be understood that the invention is not to be limited to the precise details herein illustrated and described since the same may be carried out in other ways, falling within the scope of the invention as claimed.

What I claim is:

1. An automatic firearm comprising in combination, a casing, a longitudinally reciprocable barrel having a barrel extension connected therewith and positioned within the casing, a breech block member guided on the barrel extension for downward and upward movement out of and into breech-closing position, and mechanism for moving the breech block member downward and upward in timed relation with the reciprocation of the barrel and barrel extension, in combination with a stop member carried by the barrel extension and having a portion positioned to limit downward movement of the breech block,

one of said members being formed with a recess and the other member having a projection adapted to be received in said recess when the breech block member is in engagement with said stop member to substantially prevent horizontal movement of the lower end of the breech block member in a direction transverse to the horizontal axis of the firearm.

2. An automatic firearm comprising in combination, a casing, a longitudinally reciprocable barrel having a barrel extension connected therewith and positioned within the casing, a breech block guided on the barrel extension for downward and upward movement out of and into breech-closing position, said breech block having a recess formed in the lower end thereof, and mechanism for moving the breech block downward and upward in timed relation with the reciprocation of the barrel and barrel extension, in combination with a stop carried by the barrel extension and having a portion positioned to limit downward movement of the breech block, and a projection on said stop adapted to engage said breech block recess when the breech block is in engagement with said stop, whereby horizontal movement of the lower end of the breech block in one direction is substantially prevented.

3. An automatic firearm comprising in combination, a casing, a longitudinally reciprocable barrel having a barrel extension connected therewith and positioned within the casing, a breech block guided on the barrel extension for downward and upward movement out of and into breech-closing position, said breech block having a recess formed in the lower end thereof, and mechanism for moving the breech block downward and upward in timed relation with the reciprocation of the barrel and barrel extension, said mechanism including a member adapted to engage said recess while moving said breech block upward and downward, in combination with a stop carried by the barrel extension and having a portion positioned to limit downward movement of the breech block, and a projection on said stop adapted to engage said breech block recess when the breech block is in engagement with said stop, whereby horizontal movement of the lower end of the breech block in a direction transverse to the firearm is substantially prevented.

4. An automatic firearm comprising in combination, a casing, a longitudinally reciprocable barrel having a barrel extension connected therewith and positioned within the casing, a breech block guided on the barrel extension for downward and upward movement out of and into breech-closing position, said breech block having a recess formed in the lower end thereof, and mechanism for moving the breech block downward and upward in timed relation with the reciprocation of the barrel and barrel extension, in combination with a stop carried by the barrel extension and positioned to limit downward movement of the breech block, and a projection having opposite sides tapering inward toward the top connected to said stop and adapted to engage said breech block recess when the breech block is in engagement with said stop, whereby horizontal movement of the lower end of the breech block in a direction transverse to the firearm is substantially prevented.

5. An automatic firearm comprising in combination, a casing, a longitudinally reciprocable barrel having a barrel extension connected therewith and positioned within the casing, a breech

block guided on the barrel extension for downward and upward movement out of and into breech-closing position, said breech block having a recess formed in the lower end thereof, and mechanism for moving the breech block downward and upward in timed relation with the reciprocation of the barrel and barrel extension, in combination with a relatively movable stop carried by the barrel extension and normally in a position to limit downward movement of the breech block, the said stop also being normally freely movable substantially horizontally in a direction to release the breech block, and a projection on said stop adapted to engage said breech block recess when the breech block is in engagement with said stop, whereby horizontal movement of the lower end of the breech block in a direction transverse to the firearm is substantially prevented.

6. An automatic firearm comprising in combination, a casing, a longitudinally reciprocable barrel having a barrel extension connected therewith and positioned within the casing, said barrel extension being provided with an opening

5 forming a guideway, a breech block guided on the barrel extension for downward and upward movement out of and into breech-closing position, said breech block having a recess formed in the lower end thereof, and mechanism for moving the breech block downward and upward in timed relation with the reciprocation of the barrel and barrel extension, in combination with a relatively movable stop carried by the barrel extension and normally in position to limit downward movement of the breech block, the said stop also being normally freely movable horizontally in a direction to release the breech block, a member formed on said stop and slidably disposed in said 10 guideway for guiding the movement of said stop, a projection on said stop adapted to engage said breech block recess when the breech block is in engagement with said stop to prevent horizontal movement of the lower end of the breech block 15 in a direction transverse to the firearm, and a spring disposed in said guideway and abutting the inner end of said member on said stop to bias the stop for movement to its normal position.

GEORGE WEBB.
